UNITED STATES PATENT OFFICE.

FRANK ACKERMAN, OF ST. LOUIS, MISSOURI, ASSIGNOR TO CURTIS MANUFACTURING COMPANY, OF WELLSTON, MISSOURI, A CORPORATION OF MISSOURI.

CAR-WASHING APPARATUS.

Application filed April 21, 1928. Serial No. 103,600.

This invention relates to washing apparatus of the type that comprises a nozzle from which a mixture of liquid and compressed air is discharged onto or into the object being cleaned.

One object of my invention is to provide a practicable washing apparatus by which an automobile, motor truck or other vehicle can be washed quickly, thoroughly and without liability of injuring the finish of the vehicle.

Another object of the invention is to provide a washing apparatus capable of use for various purposes, which is of such construction that the operator in charge of same can adjust it quickly and easily to change the character of the stream discharged from the mixing nozzle, and thus obtain a stream that is exceptionally efficient for cleaning the particular thing being operated on.

Another object of the invention is to provide a washing apparatus, which, in addition to having the desirable characteristics above pointed out, is compact and of sufficiently rugged construction to insure its standing up successfully under rough treatment and continuous usage.

And still another object of the invention is to provide a nozzle for washing apparatus which is of such construction that it will mix compressed air and a liquid in such a manner as to produce an air mist that has great penetrating properties and which will effectively remove dirt from an object or surface without liability of injuring said object or surface.

To this end I have devised an apparatus that comprises an air compressor, a pump preferably of the turbine type that will deliver a stream of liquid of a certain approximate pressure, irrespective of the pressure of the source of supply, an electric motor or other suitable driving means for actuating said pump and compressor, a mixing nozzle to which a liquid under pressure and compressed air are supplied, designed so that each drop of liquid will be atomized by the air into tiny particles, each of which is surrounded by a shock absorbing cushion of air, thereby producing a powerful, penetrating mist that will effectively remove dirt or other foreign matter from the object being cleaned, without injuring the object or the finish of same, an operating valve by which the operator in charge of the appara-

tus can control the supply of liquid to the mixing nozzle, and a supply valve which the operator can actuate so as to cause either clear water or a cleaning solution to be supplied to the pump. The compressor is preferably of the water-cooled type and is combined with a radiator that is connected to the intake of the pump, and the operating valve is so constructed and arranged that when it is set in its closed position to cut off the supply of liquid to the mixing nozzle, the water in the cooling system of the compressor circulates freely without creating any back pressure, thereby causing the pump to consume practically no power, notwithstanding the fact that the compressor continues in operation so as to maintain a supply of compressed air in a storage tank from which compressed air is drawn at frequent intervals to inflate pneumatic tires, or for any other purpose.

Figure 1 of the drawings is a side elevational view of a car washing apparatus constructed in accordance with my invention.

Figure 2 is a top plan view of said apparatus.

Figure 3 is a longitudinal sectional view of the mixing nozzle.

Figure 4 is an enlarged side elevational view of the supply valve; and

Figure 5 is an enlarged side elevational view of the operating valve.

Referring to the drawings which illustrate the preferred form of my invention, A designates an air compressor preferably of the water-cooled type, B designates a radiator for dissipating the heat generated in said compressor when it is in operation, C designates an electric motor or other source of power that is used to drive a belt D that passes around a pulley on the crank shaft of the compressor, E designates an automatic belt tightener for said belt, F designates a water pump, preferably of the turbine type, that is directly connected with the drive shaft of said electric motor, and G designates a storage tank into which the compressor A discharges, the compressor being provided with a governor H that automatically cuts off the supply of compressed air to the storage tank G when a certain pressure is created in said tank and which automatically resumes the supply of air to said tank when the pressure in same drops below a certain approximate degree.

The intake pipe 1 of the water pump F leads from a supply valve I and the discharge pipe 2 of said pump leads to an operating valve J, the radiator B that forms part of the cooling system of the compressor being connected with the intake pipe 1 of the pump. The supply valve I is preferably of the three-way type and is provided with a control handle 3 that is adapted to be set 10 in one position to cause clear water to pass from a supply pipe 4 to the intake pipe of the water pump F; set in a different position so as to cause soapy water or a cleaning solution to be supplied to the take pipe of the water pump through a pipe 5 that communicates with a barrel or container K which holds soapy water or some other suitable cleaning solution; and set in still a different position to cause clear water to pass from 20 the supply pipe 4 into the intake of the pump and also into the pipe 5 so as to fill the barrel K. To facilitate setting the control handle of the supply valve I in the desired position, said handle is arranged in proximity 25 to a visual indicator 3^a that is marked with the words "From water main", "From barrel" and "Fill barrel", so as to indicate the three different positions of said control handle.

30 The operating valve J is used to govern the passage of the liquid from the discharge pipe 2 of the pump F to a pipe 6 that leads to a mixing nozzle L to which compressed air is supplied by a pipe 7 that leads from 35 the compressed air reservoir G. This operating valve J is also provided with a control handle 8 that is adapted to be set in three different positions, i. e., a closed position, wherein it cuts off the passage of the 40 liquid from the discharge pipe 2 of the pump into the pipe 6 that leads to the nozzle L; a wide open position, wherein it permits the entire output of the pump to pass freely into the pipe 6; and a partly open position, 45 wherein it permits approximately one-half the volume of liquid flowing through the pump discharge pipe 2 to pass into the pipe 6 leading to the nozzle. When the control handle 8 of the operating valve is in its 50 closed position, all of the water flowing through the discharge pipe 2 of the pump will be introduced into the radiator B, and when said control handle is in its partly open position, approximately one-half the 55 volume of water flowing through the discharge pipe 2 from the pump will pass into the radiator and the remainder of said water will pass into the water supply pipe 6 which leads to the nozzle L. Consequently, when 60 the control handle of the operating valve J is in its fully closed position, the water in the cooling system of the compressor will circulate freely without producing any back pressure, and practically no power will be 65 required to operate the water pump F. To

facilitate setting the control handle 8 of the operating valve in the desired position, said handle is arranged in proximity to a visual indicator 8^a that is marked with the words "Closed", "Chassis wash" and "Body wash", 70 so as to indicate how the operating valve should be set so as to produce a stream that is most suitable for the particular portion of the car being washed. The compressed air supply pipe 7 and the water supply pipe 6 75 through which compressed air and water are conducted to the nozzle L are provided with flexible extensions 7^a and 6^a, to which said nozzle is connected, so as to enable the nozzle, which is held in the hand of the operator, to be manipulated easily. The compressed air supply pipe 7 is provided with a valve 9 that is adapted to be closed when the apparatus is not in use and set in its wide open position when the apparatus is in use. 80

The nozzle L differs from the nozzles heretofore used in washing apparatus that employ compressed air to atomize a liquid and force it against the object being cleaned, in that the mixing chamber 10 of the nozzle 90 is provided with an orifice 11 of a predetermined size through which the mixture of air and liquid is discharged from the nozzle. When the apparatus is in operation air under a fixed pressure and water under a lesser, 95 fixed pressure are fed into the mixing chamber 10 of the nozzle simultaneously. The air builds up a back pressure in the mixing chamber and intermingles with the water, and the mixture of air and water then escapes from the mixing chamber through the orifice 11, thereby producing a powerful, 100 penetrating air mist of relatively high velocity in which the water is in the form of fine droplets surrounded by shock absorbing 105 cushions of air. Notwithstanding the fact that the stream of air and water which escapes from the nozzle has a relatively high velocity and therefore great penetrating power, it is not harsh or destructive and will 110 effectively remove dirt and road oil from an automobile without injuring the finish of same.

In most instances the compressor A will be allowed to operate continuously so as to 115 keep the reservoir G charged with compressed air that can be used for inflating tires or for various other purposes. At such times the control handle of the operating valve J is set in its closed position and 120 the control handle of the water supply valve I is set in a position to cause water to pass from the supply pipe 4 into the intake pipe 1 of the water pump. Due to the fact that the operating valve is closed, the water in 125 the cooling system of the compressor will simply circulate through said system without creating any back pressure and without causing the water pump to impose a perceptible load on the electric motor or other 130

driving means C. When the apparatus is to be used for washing a car or other object, it is the usual custom to set the control handle of the operating valve J in its wide open position and set the water supply valve I so that soapy water or any other cleaning solution which may be in the barrel K will be drawn from said barrel by the water pump F and forced through the pipe 6 into the mixing chamber 10 of the nozzle, wherein said water is atomized by the compressed air which is supplied to said mixing chamber through the air supply pipe 7 whose valve 9 was set in its wide open position at the time the operating valve J was opened. The stream of air and soapy water which is discharged from the nozzle is particularly effective for removing dirt or road oil from the chassis of an automobile, and after the dirt has been removed from the chassis, the operator shifts the control handle of the water supply valve I into such a position that clear water will be admitted from the water supply pipe 4 to the water pump F, thereby causing the nozzle to discharge an air mist composed of particles of clear water surrounded by cushions of air, that is particularly effective for rinsing off the chassis. In the operation of cleaning the body of the car, the control handle of the operating handle J is set in its partly open position, so as to cause part of the water from the discharge pipe 2 of the pump to be admitted to the water supply pipe 6 leading to the nozzle and the remainder of the water from the pump discharge pipe to be directed into the radiator B of the compressor cooling system. The stream which escapes from the nozzle when the operating valve is set in its partly open position will also consist of a stream of air and water in which the particles of water are surrounded by shock absorbing cushions of air, but the pressure of said stream will be materially reduced, as it is not necessary or desirable to use a stream of so high a pressure in cleaning the body of the car. At some period during the washing operation the operator sets the control handle of the water supply valve I in its intermediate position or "Fill barrel" position, so as to cause clear water from the city main supply pipe 4 to pass through the pipe 5 into the barrel K and fill same. At the completion of the washing operation the operator moves the handle of the operating valve J into its closed position, and if desired, the valve 9 in the compressed air supply pipe 7 can be left open, so as to use the stream of air that emerges from the nozzle L to dry, inaccessible parts of the car that cannot be easily wiped off or dried with a chamois.

While I have described my improved apparatus as being primarily adapted for use as a mechanical car washer, I wish it to be

understood that it is not limited to this particular use, as an air mist of the character produced by the mixing nozzle of the apparatus is exceptionally efficient for cleaning bottles and other objects. Moreover, while I prefer to equip the apparatus with a pump of the turbine type for feeding a liquid under pressure to the mixing nozzle, any other suitable type of pump can be used and any suitable type of driving means can be used for operating the pump and the compressor.

Having thus described my invention, what I claim as new and desire to secure by Letters Patent is:

1. A washing apparatus, comprising a mixing nozzle, means for supplying air under pressure to said nozzle, a pump for feeding a liquid to said nozzle, an operating valve for controlling the admission of the liquid to the nozzle, a container for holding a cleaning solution, a source of clear water supply, and a supply valve under control of the operator in charge of the apparatus that is adapted to be manipulated to cause clear water to be admitted to said pump or cause the cleaning solution to be admitted to said pump from said container or to cause clear water to be admitted to said container from the source of clear water supply.

2. A washing apparatus, comprising a water-cooled air compressor, a radiator which forms part of the cooling system of said compressor, a mixing nozzle to which compressed air is adapted to be supplied, a pump for feeding a liquid to said nozzle arranged so as to induce a circulation in said cooling system, and an operating valve for governing the admission of the liquid to the mixing nozzle arranged so that when it is in its closed position said pump will circulate the water in the cooling system of the compressor without creating a back pressure.

3. A washing apparatus, comprising a water-cooled air compressor, a radiator that forms part of the cooling system of said compressor, a turbine water pump whose intake is connected with said cooling system, a means for driving said pump and compressor, a mixing nozzle to which compressed air is adapted to be supplied, a water supply pipe leading to said nozzle, and an operating valve for controlling the supply of water to the mixing nozzle, arranged so that it can be set in a position to direct all or a portion of the output of the pump into the cooling system of the compressor.

4. A washing apparatus, comprising a water-cooled air compressor, a radiator that forms part of the cooling system of said compressor, a turbine water pump whose intake is connected with said cooling system, a means for driving said pump and compressor, a mixing nozzle to which com-

pressed air is adapted to be supplied, an operating valve adapted to be set so as to cause water from the discharge of said pump to be admitted to said nozzle or to cause all 5 or a portion of the output of the pump to be directed into the cooling system of the compressor, a container for holding a cleaning solution, and a manually-operable supply valve that is adapted to be set in one position 10 to cause clear water to be supplied to the intake of the pump, in a different position to cause the solution from said container to be admitted to the pump and in still a different position to cause clear water 15 to be supplied to said container and also to the intake of the pump.

5. A washing apparatus, comprising a water-cooled air compressor, a radiator which forms part of the cooling system of 20 said compressor, a motor, a belt for transmitting movement from said motor to said compressor, a turbine water pump directly

connected with said motor and having its intake connected with the cooling system of the compressor, an operating valve adapted 25 to be set in one position to permit water to escape freely from the discharge of said pump to a mixing nozzle, in a different position to cause part of the discharge from said pump to be admitted to the nozzle and the remainder to be admitted to the cooling system of the compressor and in a third position to cause the entire discharge of the pump to be directed into said cooling system, a container for holding a cleaning solution, and a manually-operable supply valve by which the operator in charge of the apparatus can admit clear water to said pump or cause the solution from said container to be admitted to the pump or to 30 cause clear water to be supplied to said container and also to said pump. 35

FRANK ACKERMAN.
